Primary Examiner — Mary Ann Calabrese*Assistant Examiner* — Megan M Majcher Hartnett(74) *Attorney, Agent, or Firm* — Cantor Colburn LLP(57) **CLAIM**

We claim, the ornamental design for a display screen or portion thereof with graphical user interface, as shown and described.

DESCRIPTION

The FIGURE is a front view of a display screen or portion thereof with graphical user interface, showing our new design.

The broken lines are for environmental purposes only and form no part of the claimed design.

1 Claim, 1 Drawing Sheet(56)
